Term of patent 14 years

Int. Cl. D22—05

U.S. Cl. D22—28

FIG. 1 is a side elevation view of a fishing lure constructed in accordance with my invention, and showing one embodiment of my design.

FIG. 2 is an end elevation view depicting the fishing lure shown in FIG. 1 as it appears when viewed from the rear end thereof.

FIG. 3 is a side elevation view of the fishing lure shown in FIG. 1 as it appears when viewed from the opposite side of the lure visible in FIG. 1.

FIG. 4 is a front elevation view of the fishing lure depicted in FIG. 1, showing the lure as it appears when viewed from ahead.

FIG. 5 is a top plan view of the fishing lure shown in FIG. 1.

FIG. 6 is a bottom plan view of the fishing lure shown in FIG. 1.

FIG. 7 is a sectional view taken along line 7—7 of FIG. 1.

FIG. 8 is a side elevation view of a fishing lure constructed in accordance with the present invention, and showing a second embodiment of the design of the invention.

FIG. 9 is an end elevation view showing the fixed fishing lure depicted in FIG. 8 as it appears when viewed from the rear of the lure.

FIG. 10 is a side elevation view of the fishing lure depicted in FIG. 8.

FIG. 11 is a front elevation view of the fishing lure depicted in FIG. 8.

FIG. 12 is a top plan view of the fishing lure depicted in FIG. 8.

FIG. 13 is a bottom plan view of the fishing lure depicted in FIG. 8.

FIG. 14 is a sectional view taken along line 14—14 of FIG. 8.

FIG. 15 is a side elevational view of a fishing lure constructed in accordance with the present invention and showing yet another embodiment of my design. The fishing lure depicted in FIG. 15 appears in all other respects, except for the side elevation view there shown, the same as the other embodiments of my invention depicted in the drawings.

Hooks are depicted in the drawings in dashed lines for illustrative purposes, and form no part of the present invention.

I claim:

The ornamental design for a fishing lure, substantially as shown and described.
